UNITED STATES PATENT OFFICE.

CHARLES M. LEFLER, OF WINSTON, MONTANA.

GRAIN-WEIGHER.

1,358,003.

Specification of Letters Patent.

Patented Nov. 9, 1920.

Application filed August 20, 1919. Serial No. 318,810.

To all whom it may concern:

Be it known that I, CHARLES M. LEFLER, a citizen of the United States, residing at Winston, in the county of Broadwater and 5 State of Montana, have invented certain new and useful Improvements in Grain-Weighers, of which the following is a specification.

This invention relates to a grain weighing device, and an object of the invention is to 10 provide a grain weighing device which is self contained, requiring no power for the operation thereof, and one which is simple in construction, and may be manufactured 15 at a relatively low cost.

More specifically, the invention comprehends the provision of a grain weigher comprising a body or grain receiving housing divided into a pair of compartments, and 20 having a pair of rockable valve members carried thereby one of which controls the inlet of grain into the compartment while the other controls the outlet of grain from the compartments, which valve members are 25 connected for synchronous movement, whereby when one of the valve members opens to allow the grain to pass out of the compartment the other will move into a closing position to prevent the entrance of grain there- 30 into, and to associate with said valve a spring, of the contractile spiral type, the tension of which regulates the quantity of grain measured upon each operation of the weigher and which will, when the closing 35 valve reaches its dead center swing the closing valve into a closing position with respect to the compartment which is at such time receiving the grain.

A further object of the invention is to 40 provide an attachment for grain weighers, including a spring controlled striking lug carried by a disk which is connected to the valve and controls the inlet of grain into the compartment, the said pin being adapted 45 for striking engagement with a counter of any approved type to register each predetermined quantity of grain measured by the apparatus.

Other objects of the invention will appear 50 in the following detailed description taken in connection with the accompanying drawings, forming a part of this specification, and in which drawings:

Figure 1 is a side elevation of the im- 55 proved grain weigher.

Fig. 2 is a vertical section of the grain weigher taken on the line 2-2 of Fig. 1.

Fig. 3 is a vertical section through the grain weigher taken transversely to the section illustrated in Fig. 2.

Fig. 4 is a horizontal cross section taken on the line 4-4 of Fig. 3.

Fig. 5 is a detail enlarged side elevation of the tensioning means for the spring.

Fig. 6 is a detail section taken on the line 6-6 of Fig. 5.

Fig. 7 is a detail section taken on the line 7-7 of Fig. 1 and illustrating the counter operating pin, and

Fig. 8 is a detail perspective of the inlet 70 controlling valve.

Referring more particularly to the drawings, wherein like characters indicate like and corresponding parts throughout the several views, the main body or housing of 75 the weighing attachment 10 is preferably formed of sheet metal, and in a rectangular shape. However it is to be understood that any practical shape may be employed, for the body 10 without departing from the 80 spirit of this invention. A vertically extending partition 11 is placed within the body 10 and divides the same into compartments 12 and 13 each of which open out at the upper and lower ends of the body. The 85 receiving member 14 is attached to or formed upon the upper end of the housing or body 10 and it is provided with a constricted grain receiving mouth 15 while a similar delivery member 16 is attached to or formed 90 upon the lower end of the body 10 and it also has a constricted outlet 17, as clearly shown in Figs. 1 and 3 of the drawings.

Positioned at the upper end of the body 10 equidistant of its edges, is a rockable shaft 95 18, which has a disk 19 mounted thereon exteriorly of the housing, and a valve member 20 keyed thereon interiorly of the housing and riding in the inlet or receiver 14 of the weighing attachment. This valve 20 is 100 substantially pyramidal in shape, having the opening 21 at its apex which receives the shaft 18 therethrough, and its outer end or base 22 is arcuated, as clearly shown in the drawings, to form a snug fit between the 105 arcuate portions of the walls of the receiver 14 to prevent the passage of grain therebetween. Stops 23 and 24 are carried by the arcuate portions of the walls of the receiver 14, and limit the movement of the valve 20. 110

A second shaft 25 is supported by the body 10 at its lower end, and it has an outlet control valve 26 mounted thereon. The valve 26 is similar in shape to the valve 20, however, it is larger in size and consequently much greater in width. The tangent or circumference of the base portion of the valve 26 is substantially equal to the width of the throat 17, so that when the valve 26 is in a vertical position upon its dead center, it will practically close the outlet or throat 17 and prevent the passage of grain thereinto, as will be hereinafter more fully described. Stops 27 and 28 are provided within the body 10 to limit the movement of the valve 26. A disk 29 is mounted upon the outer end of the shaft 25. The rod 30 eccentrically connects the disks 19 and 29, and subsequently the shafts 13 and 25 for synchronous movement. A bolt or lug 31 is carried by the disk 29 and extends through a block 32, slidably carried by a frame 33. An adjusting bolt 33' is connected to the block 32, for adjusting its position with respect to the frame 33 and this block 32 is provided with an aperture 34 which is mounted over the pin or lug 31 for connecting the block to the disk 29. The frame 33 has a spiral spring 35 of the contracting type connected thereto, which spring is also connected to a pin 36, carried by the disk 19. This spring is connected to each of the disks, at slightly offset points with respect to their axis, so that the contracting action of the springs will rock the valve and shafts 18 and 25 when the valves 20 and 26 are upon dead center, thus positively insuring the operation of the weighing attachment.

In use, the valve 20 forms a closure for one of the compartments as shown in Fig. 3, forming a closure for the compartment 13 to prevent grain from entering the said compartment at which time the valve 26 forms a closure for the lower end of the compartment 12 to prevent grain from passing out of this compartment. When the valve is so placed, the grain passing through the receiver 14 will be guided into the compartment 12. As the quantity of grain within the compartment 12 increases, it will gradually force the valve 26 downwardly at the same time tensioning the spring 35 and this gradual downward forcing of the valve 26 will gradually move the valve 20 over toward the stop 24 for cutting off the feeding of grain into the compartment 12 owing to the connection between the shafts 13 and 25 which is established by the disks 18 and 29 and the rod 30. However, the valve 20 does not close the compartment 12 until after the valve 26 has assumed its vertical position or is on dead center, and even then it is placed so that a slight amount of grain may pass into the compartment 12 and when the valve 26 reaches such position the spring

35 will be under tension and immediately as the valve 26 tends to move slightly off in dead center, the spring 35 will act to quickly snap the valve 26 upwardly into engagement with the stop 28 to form a closure for the compartment 13 at which time the valve 20 will be moved to form a closure for the inlet end of the compartment 12 and to allow the grain to pass downwardly through the compartment 13. The disk 19 is provided with a recess 38, formed therein and having an opening upon the upper portion of the disk, in which recess the tension spring 39 is positioned. This spring engages against the head 40 formed upon a striking pin 41. The head 40 of striking pin 41 is confined within the recess 38, by a threaded washer 42, while the main portion of the pin projects beyond the periphery of the disk 19, for striking engagement with a counter 44, of any approved type for registering each operation of the valve 20, and consequently registering the number of predetermined quantities of grain measured or weighed by the weigher.

The tension of the spring 35 may be regulated by the adjusted movement of the block 32 to weigh any predetermined quantity of grain upon each operation of the valves, or cause it to weigh a desired quantity of various types of grain having different specific gravities, such as wheat, oats, rye, etc.

Changes in details may be made without departing from the spirit of this invention,

100

I claim:

1. In a grain weigher, the combination of a body divided into a pair of grain receiving chambers, a valve pivoted at the upper end of the division of said chamber for controlling the inlet of grain into the chamber, a second valve positioned at the lower end of the division of said chamber and controlling the outlet of grain from the chamber, said valve connected for synchronous movement and arranged whereby the inlet control valve will prevent the inlet of grain into the chamber other than that which is closed by said outlet control valve, stops within said body for limiting the movement of said valves, and a weighing contractile spring connecting said valves and adapted to swing them past the dead center and into proper positions after operation thereof under weight of grain.

2. In a grain weigher, the combination of a body divided into a pair of grain receiving chambers, a valve pivoted at the upper end of the division of said chamber for controlling the inlet of grain into the chamber, a second valve positioned at the lower end of the division of said chamber and controlling the outlet of grain from the chamber, said valve connected for synchronous movement and arranged whereby the

110

125

130

- inlet control valve will prevent the inlet of grain into the chamber other than that which is closed by said outlet control valve, stops within said body for limiting the movement of said valves, a weighing contractile spring connecting said valves and adapted to swing them past their dead center and into proper closing position after operation thereof under weight of grain, and means for tensioning said spring.
3. In a grain weigher, the combination of a body divided into a pair of grain receiving compartments, shafts, rockably supported by said body at the lower and upper ends of the partition forming said chamber, valve members keyed to said shafts and extending into opposite directions whereby the upper valve will form a closure for one chamber at its upper end, while the lower valve will form a closure for the other chamber at its lower end, disks mounted upon said shafts exteriorly of said body, means connecting said disks for connecting said valves for synchronous movement, a weighing contractile spring connected to said disks, and means for tensioning said spring.
4. In a grain weigher, the combination of a body divided into a pair of grain receiving compartments, shafts rockably supported by said body at the lower and upper ends of the partition forming said chamber, valve members keyed to said shafts and extending into opposite directions whereby the upper valve will form a closure for one chamber at its upper end, while the lower valve will form a closure for the other chamber at its lower end, disks mounted upon said shafts exteriorly of said body, means connecting said disks for connecting said valves for synchronous movement, a weighing contractile spring connected to said disks, and means for tensioning said spring.

CHARLES M. LEFLER.
